UNITED STATES PATENT OFFICE.

WILBUR M. STONE, OF NEW YORK, N. Y., ASSIGNOR TO ARTHUR CONROW, TRUSTEE,
OF NEW YORK, N. Y.

NOTE-SHEET-GUIDING DEVICE.

1,105,046.

Specification of Letters Patent. Patented July 28, 1914.

Application filed October 7, 1911. Serial No. 653,345.

To all whom it may concern:

Be it known that I, WILBUR M. STONE, a citizen of the United States, and a resident of New York, in the county of Kings and 5 State of New York, have invented certain new and useful Improvements in Note-Sheet-Guiding Devices, of which the following is a specification.

This invention relates to note-sheet guiding devices for automatic musical instruments and has for its object to provide a device of the class specified, efficient in operation and simple in construction.

With these ends in view my improvements 15 comprise parts and combinations of parts illustrated in the accompanying drawing in which I have shown the preferred embodiment of my invention.

Figure 1 is a general front elevation partly 20 in section. Fig. 2 is a fragmentary sectional elevation illustrating the operation of a portion of my device. Fig. 3 is a sectional elevation illustrating an alternate construction of a portion of my device, the section 25 being taken on line *a*—*a* of Fig. 5. Fig. 4 is a sectional elevation similar to that of Fig. 3, the section being taken on line *b*—*b* of Fig. 5. Fig. 5 is a sectional plan view, the section being taken on line *c*—*c* of 30 Fig. 3.

Music rolls 2 and 4 are rotatably mounted in side frames 3 and 5 and roll 4 may be actuated by means of its shaft 40 from some source of power not shown, to draw 35 note-sheet 6 across tracker-bar 7. Said tracker-bar is mounted for movement in the direction of its length transverse the path of travel of note-sheet 6 in bearings in side-frames 3 and 5 and may be provided 40 with the usual music apertures 8, 8. Note-sheet 6 is provided with the usual perforations 9, 9 which, as said note-sheet is drawn across tracker-bar 7 register with corresponding apertures 8, 8 in said tracker-bar 45 thereby admitting atmosphere through said apertures to the usual ducts not shown, whereby the mechanism of the musical instrument is set in motion to sound the notes indicated by the note-sheet perforations all 50 as well-known in the art. Adjacent to one edge of the normal path of said note-sheet, tracker-bar 7 is provided with a single guide opening 10 communicating by pipe 12 with pneumatic means operable through suitable 55 mechanical connections for moving said

tracker-bar endwise in either direction as the case may be for maintaining correct registration between the perforations in the note-sheet and the apertures in the tracker-bar. Said pneumatic and mechanical means 60 comprise a single actuating pneumatic 11 which is actuated by atmospheric pressure alternately in opposite directions and which pneumatic has its movable wall 13 connected by link 15 to tracker-bar 7. Said movable 65 wall is preferably provided with an overhanging portion 14 having ear 16 fixed thereto and which ear is pivotally connected to said link 15.

For working actuating pneumatic 11 in 70 opposite directions by atmospheric pressure I preferably inclose it in a chamber 17 and secure fixed wall 18 of said pneumatic to some suitable support as post 19 of said chamber. Overhanging portion 14 of movable 75 wall 13 projects outwardly through opening 21 in said chamber 17 and is provided with a flexible air-dam 20 to prevent leakage. Pneumatic 11 and chamber 17 are each provided with both atmospheric and 80 vacuum connections and means are provided for simultaneously admitting atmosphere to said pneumatic and vacuum to said chamber or vice versa. While said means may have any one of a variety of embodiments I pref- 85 erably employ a single valve member 22 preferably cylindrical and slidably mounted in a corresponding cylindrical seat or chamber 28. Said valve 22 has two ports 23, 24 therearound. Said valve is operated 90 alternately in opposite directions by atmospheric pressure; downwardly by direct pressure of the atmosphere and upwardly by indirect pressure through primary pneumatic 95 25.

Vacuum chamber 26 is provided with pipe 27 leading therefrom to some source of exhaust not shown. Vacuum passage 29 from chamber 26 and atmospheric passage 30 are merged into common passage 31 leading into 100 actuating pneumatic 11. Atmospheric passage 32 and vacuum passage 33 are merged into common passage 34 leading into chamber 17. Passages 29, 30, 32 and 33 are preferably arranged in parallelism in one plane. 105 Valve chamber 28 is open at one end to vacuum chamber 26 and at the other end to the atmosphere. Said chamber severs each of said passages 29, 30, 32 and 33 in the common plane normal thereto. Primary 110

pneumatic 25 within vacuum chamber 26 is connected with pipe 12 leading to guide opening 10 and is provided with bleed hole 35 communicating with vacuum chamber 26. 5 Valve 22 has stem 36 at one end thereof terminating in button 37 for engagement with primary pneumatic 25. Stem 38 projects from the other end of said valve 22 and has adjustable stop nuts 39, 41 threaded thereon 10 for engagement with arm 42 upstanding from the wall of valve chamber 28, for limiting the stroke of valve 22.

In Figs. 3, 4 and 5 I have illustrated one modification of valve arrangement wherein 15 I employ rotary valve 52 having ports 53, 54 for at one time admitting vacuum to actuating pneumatic 11 and atmosphere to chamber 17 and at another time admitting atmosphere to said pneumatic and vacuum to 20 said chamber. Said valve 52 is rotatably mounted in seat 51 of valve box 55 having passage 56 open to atmosphere and passage 57 connected with vacuum chamber 26. Pipe 31 leads from one side of valve seat 51 to 25 pneumatic 11 and pipe 34 leads from the other side of said seat to chamber 17. Stem 58 of valve 52 has arm 59 thereof connected to primary pneumatic 25 by link 60 and spring 61 connects said arm with wall 46 30 of vacuum chamber 26 for returning valve 52 to the position of Fig. 3 after pneumatic 25 has been expanded by atmosphere to move arm 59 from its full line position of Fig. 4 to the dotted line position of said figure. It 35 will be obvious to those skilled in the art that said valve 52 may be returned by atmospheric pressure instead of by spring 61, to the position of Fig. 3, as for instance by means of a plunger similar to valve 22 of 40 Fig. 1.

The operation of my improved device is as follows: Referring first particularly to Figs. 1 and 2 and assuming that guide-opening 10 is covered by note-sheet 6, primary 45 pneumatic 25 will be collapsed by the downward movement of valve 22 under the pressure of atmosphere on the head thereof, Fig. 1. Port 24 is thereby in line with vacuum passage 29 to pneumatic 11 and port 23 is 50 in line with atmospheric passage 32 to chamber 17. Said pneumatic 11 will therefore be collapsed by atmospheric pressure on its exterior against vacuum in its interior, thereby shifting tracker-bar 7 to the left. Guide-opening 10 in said tracker-bar is thereby uncovered by being moved out from under note-sheet 6 and atmosphere is admitted to primary pneumatic 25. Said pneumatic thereupon expands moving valve 22 upwardly, causing port 24 to register with atmospheric passage 30 to actuating pneumatic 11 and port 23 to register with vacuum passage 33 to chamber 17. Said pneumatic 55 60 65 70 75 80 85 90 95 100 105 110 115 120 125 130 pneumatic pressure within against vacuum with-

out thereby shifting tracker-bar 7 to the right and restoring guide-opening 10 to covered condition by note-sheet 6. Atmosphere is thus shut off from primary pneumatic 25 which thereupon collapses under the downward movement of valve 22, and the several parts are again as shown in Fig. 1. In actual operation guide-opening 10 will fluctuate back and forth through a very short stroke whereby the edge of said guide-opening will be rapidly covered and uncovered and valve 22 will flutter up and down through a correspondingly short stroke from the mid-portion shown in Fig. 2. The apparatus is thus constantly in unstable equilibrium and if said note-sheet 6 deviates from its normal path of travel one way or the other its edge 600 will be closely followed by guide-opening 10, thereby constantly maintaining the predetermined relation between said note-sheet and tracker-bar and therefore between the perforations in the note-sheet and the apertures in the tracker-bar.

The operation of the rocking valve of Figs. 3, 4 and 5 is essentially similar to the operation of the sliding valve of Fig. 1 and may be briefly described as follows: When atmosphere is admitted through pipe 12 to primary pneumatic 25 said pneumatic expands and through link 60 rotates valve 52 from its position of Fig. 3 to connect passage 31 of pneumatic 11 with atmosphere and passage 34 of chamber 17 with vacuum. If then atmosphere be cut off from pipe 12 said primary pneumatic will be collapsed by the pull of spring 61 and valve 52 will be returned to the position of Fig. 3 wherein vacuum is being admitted to pneumatic 11 and atmosphere to chamber 17.

I claim:—

1. A note-sheet guiding device including in combination, a tracker-bar, a music roll, a winding roll for unwinding a note-sheet from said music roll and drawing it across said tracker-bar, a guide opening appurtenant to said tracker-bar adapted to be alternately covered and uncovered by said note-sheet, a chamber, an actuating pneumatic therein pneumatically operable in either direction for shifting said tracker-bar transversely of the note-sheet in either direction respectively, a valve for governing said pneumatic, means for moving said valve, the movement of which valve is constantly governed but not produced by the presence or absence of lateral movement of the note-sheet in either direction relatively to said guide opening, means for moving the tracker-bar from the actuating pneumatic, and means for connecting the device with vacuum producing means.

2. A note-sheet guiding device including in combination, a tracker-bar, a music roll, a winding roll for unwinding a note-sheet

from said music roll and drawing it across said tracker-bar, a guide opening appurtenant to said tracker-bar, adapted to be alternately covered and uncovered by said 5 note-sheet, a chamber, an actuating pneumatic therein pneumatically operable in either direction, for shifting said tracker-bar transversely of the note-sheet in either direction respectively, a unitary valve independent 10 of said pneumatic, for governing said pneumatic, and which valve is actuated by atmosphere alternately in opposite directions, the admission of atmosphere to said valve being constantly governed by the presence 15 or absence of lateral movement in either direction of the note-sheet relatively to said guide opening, means for moving said tracker-bar from the actuating pneumatic, and means for connecting the device 20 with vacuum producing means.

3. In a note-sheet guiding device employing a tracker-bar and a note-sheet traveling thereover, the combination of a chamber, a single actuating pneumatic therein pneumatically operable in either direction for shifting the tracker-bar in either direction respectively transversely of the note-sheet, a unitary valve independent of said pneumatic for governing said pneumatic, a single 25 guide opening in said tracker-bar adapted to be alternately covered and uncovered by the note-sheet, means for actuating the valve from the guide opening, means for actuating the tracker-bar from said pneumatic, 30 and means for connecting the device with vacuum producing means.

4. A note-sheet guiding device including in combination, a note-sheet, a tracker-bar having a guide opening therein, adapted to 40 be alternately covered and uncovered by said note-sheet, a winding roll for drawing said note-sheet across said tracker-bar, an actuating pneumatic, a chamber in which said pneumatic is inclosed, a valve, for at 45 one time letting atmosphere into said pneumatic and also out of said chamber and at another time for letting atmosphere out of said pneumatic and also into said chamber, the movement of which valve is constantly 50 governed but not produced by the presence or absence of lateral movement of the note-sheet relatively to said guide opening, means for actuating the tracker-bar from said pneumatic, and means for connecting the 55 device with vacuum producing means.

5. A note-sheet guiding device including in combination, a tracker-bar, a note-sheet,

a winding roll for drawing said note-sheet across said tracker-bar, a single guide-opening appurtenant to said tracker-bar adapted to be alternately covered and uncovered by said note-sheet, a single actuating pneumatic, a chamber in which said pneumatic is inclosed, means for at one time letting atmosphere into said pneumatic and also out of said chamber and at another time for letting atmosphere out of said pneumatic and also into said chamber for moving said tracker-bar transversely of said note-sheet; means, governed by the covering or uncovering of said single guide opening, for actuating the means for letting atmosphere into and out of said pneumatic and chamber respectively, means for connecting said tracker-bar and said pneumatic, and means for connecting the device with vacuum producing means.

6. A note-sheet guiding device including in combination, a tracker-bar, a note-sheet, a winding roll for drawing said note-sheet across said tracker-bar, a single guide-opening appurtenant to said tracker-bar adapted to be alternately covered and uncovered by said note-sheet, a single actuating pneumatic, a chamber in which said pneumatic is inclosed, a unitary valve for at one time letting atmosphere into said pneumatic and also out of said chamber and at another time for letting atmosphere out of said pneumatic and also into said chamber for moving said tracker-bar transversely to said note-sheet, means, governed by the covering or uncovering of said single guide-opening, for actuating said unitary valve, means for connecting said tracker-bar and said pneumatic, and means for connecting the device with vacuum producing means.

7. A note-sheet guiding device including in combination, an actuating pneumatic, a chamber in which said pneumatic is entirely inclosed, a unitary valve for at one time letting atmosphere into said pneumatic and out of said chamber and at another time out of said pneumatic and into said chamber, and means for connecting the device with vacuum producing means.

Signed at New York, N. Y., this 6th day of October, 1911, before two subscribing witnesses.
